RAILWAY SIGNALING SYSTEM

Arthur L. Jerome, Edgewood, Pa., assignor to The Union Switch & Signal Company, Swissvale, Pa., a corporation of Pennsylvania

Application April 25, 1944, Serial No. 532,603

13 Claims. (Cl. 246—33)

My invention relates to a railway signaling system for use on stretches of single track through which traffic may move in either direction but only in one direction at one time.

An object of the invention is to provide an improved system which is arranged so that a change in the established direction of traffic in the protected track stretch is effected by operation of a device located at the point at which it is desired to enter the stretch.

A further object of the invention is to provide an improved system of the type described which is arranged so that the established direction of traffic cannot be changed while the stretch is occupied.

Another object of the invention is to provide an improved system of the type described which is arranged so that an attempted change in the established direction of traffic is ineffective if the stretch is occupied.

A further object of the invention is to provide an improved system of the type described which is arranged so that the established direction of traffic is altered only when a special type of energy is transmitted over the rails of the track stretch to thereby prevent interference with the established direction of traffic by traffic or other conditions.

Another object of the invention is to provide a system of the type described which is arranged so that, when the direction of traffic is to be changed, traffic reversing energy is supplied to the stretch at the end thereof at which it is desired to enter the stretch and is cascaded through all of the sections to the other end of the stretch and must be received at the other end of the stretch before a change is made in the established direction of traffic.

A further object of the invention is to provide a system of the type described which is arranged so that, when the direction of traffic is to be changed, the supply of traffic reversing energy to the track stretch is maintained until the traffic reversing function is completed.

Another object of the invention is to provide a system of the type described which incorporates means to provide an indication of occupancy of the protected track stretch.

A further object of the invention is to provide a system of the type described which operates without line wires, and in which all functions are performed by energy transmitted over the rails of the track stretch.

Another object of the invention is to provide a system of the type described which incorporates

means for normally interrupting the supply of energy to the lamps of the wayside signals for the established direction of traffic, but effective on movement of a train through the stretch to supply energy to the lamps of the signals for the portion of the stretch in advance of the train.

A further object of the invention is to provide an improved signaling system of the type shown in Letters Patent of the United States No. 10 2,316,961, issued April 20, 1943, to R. R. Kemmerer.

Other objects of the invention and features of novelty will be apparent from the following description taken in connection with the accompanying drawings.

I shall describe one form of railway signaling system embodying my invention and shall then point out the novel features thereof in claims.

In the drawings:

- 20 Figures 1A, 1B, 1C and 1D, when placed together in the order named, form a diagram showing a stretch of railway track equipped with one form of signalling system provided by my invention, and
- 25 Figure 2 discloses a modification of the pick-up circuit for a relay of Figure 1A.

Similar reference characters refer to similar parts in both views.

In practicing my invention, I provide each 30 track section in the track stretch with two sets of coded track circuit apparatus and govern them by directional stick relays so that one set of track circuit apparatus is operated by master code and the other set is operated by feed-back 35 energy according as the stretch is conditioned for one direction of traffic or the other. When the stretch is conditioned for either direction of traffic, energy of traffic governing code frequency is supplied to the stretch at the exit end 40 of the stretch and is repeated through the various sections to control traffic in the stretch, while feed-back energy is supplied over the section rails in the opposite direction and controls lighting of the wayside signals and also controls means 45 at the exit end of the stretch to indicate whether or not the stretch is occupied. The supply of feed-back energy to each section is dependent upon the supply of feed-back energy over the rails of the adjacent section in the rear so that 50 when a train enters the stretch the supply of feed-back energy over all of the sections in advance of the train is cut off.

When the established direction of traffic is to be changed, the supply of traffic governing coded 55 energy to the exit end of the stretch is cut off

and coded energy of a distinctive traffic reversing frequency is substituted therefor. This energy operates the track circuit apparatus for the various sections to release the directional stick relays and cause energy of this frequency to be repeated to the next section until it is received at the far end of the stretch where it energizes a directional relay and causes traffic governing energy to be supplied to the stretch at that point. This traffic governing energy feeds back through the traffic reversing energy and picks up directional stick relays to cut off the supply of traffic reversing energy to the section and cause traffic governing energy to be supplied to the next section. When traffic governing energy is received at the original exit end of the stretch, the supply of traffic reversing energy is discontinued, while the supply of feed-back energy over the section rails is initiated and is repeated to the new exit end of the stretch.

The supply of traffic reversing energy to the stretch is controlled by the supply of feed-back energy over the rails of the stretch so that energy of this type can only be supplied to the stretch when the stretch is vacant.

Referring to the drawings there is shown there in a stretch of single track railway having track rails 1 and 2 over which traffic may move in either direction. Adjacent the left-hand or west end of the single track stretch is a passing siding or branch track WPS, and adjacent the right-hand or east end of the single track stretch is a passing siding or branch track EPS.

Although this system is illustrated in connection with a single track stretch joining two passing sidings or branch tracks, the system is not limited to use in situations of this kind and may be employed wherever traffic may move in either direction between two points, but only in one direction at one time.

The track rails 1 and 2 are divided by insulated joints 3 into track sections for signaling purposes. As shown, there is a detector section WT which includes the switch connecting the passing siding WPS with the main track, and a detector section ET which includes the switch connecting the passing siding EPS with the main track. The single track stretch between sections WT and ET is divided into track sections 1T, 2T and 3T, but it is contemplated that the single track stretch may include a larger or a smaller number of track sections.

The detector track sections WT and ET may be provided with track circuits of any appropriate type and, as shown, each of these sections is provided with a track circuit employing steady energy and including a track relay designated TR with an appropriate prefix.

Each of the track sections 1T, 2T and 3T is provided with coded track circuit apparatus arranged so that master code energy is at times supplied to the section rails at one end of the section and feed-back energy is supplied to the other end of the section, while at other times master code energy is supplied to the other end of the section and feed-back energy is supplied to the one end of the section.

The track circuit apparatus for each section includes a code following relay at each end of the section, and each of these relays serves at times as the track relay and at other times as the feed-back detector relay.

Each code following relay has associated there-with a battery TB which serves at times as a source of master code current and at other times

as a source of feed-back current, while connection of each relay and each battery across the section rails is governed by a relay CTM which serves at times as a coding relay to cause master code impulses to be supplied to the section rails, and which serves at other times as an impulse relay to cause impulses of feed-back energy to be supplied to the section rails.

The code following relays are of the polar biased neutral type, while the energy supplied from the batteries to the section rails is supplied through the windings of the relays as shown in Letters Patent of the United States No. 2,286,002 to Frank H. Nicholson to prevent energization of the relay in the event of overlapping contacts on the associated coding or impulse relay, or by inductive energy from the track circuit.

Movement of traffic from left to right or east-bound is governed by signals ES, while movement of traffic from right to left or westbound is governed by signals WS. As shown, these signals are of the color light type, and each has a green or clear lamp G, a yellow or caution lamp Y, and a red or stop lamp R. While the signals are shown as being of the color light type, the system is not limited to the use of wayside signals of this type and any appropriate type of wayside signal may be employed.

Similarly, this signaling system is not limited to use in track stretches in which movement of traffic is governed by wayside signals and is adapted for use in track stretches in which movement of traffic is controlled by cab signals, either alone or in conjunction with wayside signals.

A directional control relay MR is provided at each end of the track stretch and each of these relays controls the supply of traffic reversing energy to the track rails at that end of the track stretch. Each relay MR is provided with a pick-up circuit controlled by a normally open push button PB, and with a stick circuit controlled by its own front contact and by a back contact of the clear signal control relay at that location.

While the pick-up circuits of the directional control relays are shown as being established by push buttons, the system is not limited to this arrangement, and these circuits may be controlled by remote control apparatus which may be of the type shown in Letters Patent of the United States No. 2,229,249 issued January 21, 1941, to Lloyd V. Lewis.

If this system is controlled by remote control apparatus, such as a C. T. C. system, a contact of a relay of the C. T. C. system is connected in multiple with each push button so that the C. T. C. system may be operated to establish a pick-up circuit for each directional control relay. If the system is controlled by a C. T. C. system, the push buttons provide means for locally controlling the direction of traffic in the event the C. T. C. system is not functioning.

Each location is provided with a source of direct current, such as a storage battery not shown, the terminals of which are designated B and C in the drawings.

The equipment is shown in the condition which it assumes when the stretch is vacant and is prepared for westbound traffic.

At this time, relay WDR at the west end of the stretch is energized by current supplied over its stick circuit which includes its own front contact 10 and back contact 11 of relay EFR. As relay WDR is picked up, relay 1ECTM is connected over front contact 12 of relay WDR, front contact 14 of relay WTTR, and traffic controlled

contact 15 to a contact of the code transmitter 120CT so that relay 1ECTM operates at the 120 code rate. The contact 15 is governed by traffic conditions in the main track at the left of section WT and is picked up when and only when this portion of the stretch is vacant.

At this time, energy is supplied over front contact 16 of relay WTTR and front contact 17 of relay WDR to the red lamp R of signal 1ES and it is lighted to prevent entrance of an eastbound train into the stretch while it is conditioned for westbound traffic.

During the picked-up periods of relay 1ECTM energy is supplied from battery 1WTB over contact 20 and through the winding of relay 1ETR to the rails of section 1T, while during the released periods of relay 1ECTM the track winding of relay 1ETR is connected across the section rails. In addition, when relay 1ECTM is released, its contact 21 permits energy to be supplied over front contact 22 of relay 1ETR and front contact 23 of relay WDR to the holding winding of relay 1ETR.

The energy of 120 code frequency supplied to the rails of section 1T as a result of coding operation of relay 1ECTM feeds over back contact 25 of relay 1WCTM to the track winding of relay 1WTR and operates the relay so that the two portions of the primary winding of the decoding transformer 1WDT are alternately energized and energy is induced in the transformer secondary windings. Energy from one of the transformer secondary windings is rectified by a contact of the relay 1WTR and is supplied to the relay 1WH and its contacts are picked up.

At this time, the relay 1WSR is energized by current supplied over its stick circuit which includes its own front contact 26 and back contact 27 of the associated relay 1WJ, and its contacts are picked up so that energy is supplied from the decoding transformer 1WDT to relay 2D over the circuit which is traced from a terminal of a secondary winding of transformer 1WDT over front contact 29 of relay 1WSR and back contact 30 of relay 1ESR to one terminal of the resonant rectifier unit 120DU, and from the other terminal of this unit over back contact 31 of relay 2ESR and front contact 32 of relay 2WSR to the other terminal of the transformer secondary winding. As the relay 1WTR is operated by energy of 120 code frequency, energy is supplied through the resonant rectifier unit 120DU to relay 2D and its contacts are picked up to permit energy to be supplied to the green lamp G of signal 1WS when a westbound train enters the stretch.

As relay 1WSR is picked up, and as relay 2EH is picked up, as explained below, energy is supplied from a secondary winding of transformer 1WDT over front contact 33 of relay 1WH, back contact 34 of relay 1WJ, front contact 35 of relay 2EH, and front contact 36 of relay 1WSR to relay 1WCTM. The relay 1WCTM and the corresponding relays at other points in the system are of a type the contacts of which pick up only when energy of a particular polarity is supplied thereto, while the apparatus is arranged so that energy of the polarity effective to pick up the contacts of relay 1WCTM is supplied to the relay on release of the relay 1WTR. Accordingly, each time the contacts of relay 1WTR release the contacts of relay 1WCTM pick up momentarily so that energy is supplied from battery 1ETB over front contact 25 of relay 1WCTM through

the track winding of relay 1WTR to the rails of section 1T.

The energy supplied from battery 1ETB to the rails of section 1T feeds over back contact 26 of relay 1ECTM to relay 1ETR and its contacts pick up so that contact 22 establishes the circuit of the relay holding winding to keep the relay picked up until relay 1ECTM picks up, whereupon relay 1ETR releases. As a result of code following operation of relay 1ETR energy is supplied through the transformer 1EDT to the relay 1EH and its contacts are picked up, while energy is not supplied to relay 1ED as its circuit is interrupted by contact 68 of relay WDR.

At this time, energy of 120 code frequency is supplied to relay 2ECTM over the circuit which includes front contact 38 of relay 1WH, back contact 39 of relay 1WJ, front contact 40 of relay 1WSR, and back contact 41 of relay 2ESR, so relay 2ECTM operates to supply master code energy of 120 code frequency to the rails of section 2T, and the equipment at the junction between sections 2T and 3T operates in the manner explained in detail in connection with the equipment at the junction between sections 1T and 2T to cause master code of 120 code frequency to be supplied to the rails of section 3T and to cause feed-back energy to be supplied to the rails of section 2T.

The energy of 120 code frequency supplied to the rails of section 3T operates the track relay 3WTR so that energy is supplied through transformer 3WDT to relays 3WH and 3WD and their contacts are picked up so that relay 3WHP is picked up and energy is supplied to the green lamp G of signal 3WS over the circuit which includes front contact 42 of relay ETTR, back contact 43 of relay EDR, front contact 44 of relay 3WHP, and front contact 45 of relay 3WD. Accordingly, the green or clear lamp G of signal 3WS is lighted to indicate to westbound trains that they may enter the stretch and that there are two unoccupied sections in advance of the stretch.

At this time, energy is supplied from a secondary winding of transformer 3WDT to relay 3WCTM over front contact 46 of relay ETTR, back contact 52 of relay WFR, back contact 103 of relay 3WJ, front contact 47 of relay 3WHP, and back contact 48 of relay EDR so the relay 3WCTM operates to supply feed-back energy to the rails of section 3T and relay 3ETR operates and maintains relay 3EH picked up. When relay 3ETR picks up, its contact 50 establishes a circuit for the relay holding winding to keep the relay contacts picked up until relay 3ECTM picks up. The circuit of the holding winding of relay 3ETR includes front contact 51 of relay 2WSR so the circuit is established only when the stretch is conditioned for westbound traffic which is the only time the relay 3ETR is operated by feed-back current and is the only time this circuit is required. A similar circuit is provided for relay 2ETR and is controlled by a contact of relay 1WSR.

As relay 3EH is picked up its contact 53 establishes the circuit for supplying energy from a secondary winding of transformer 2WDT to relay 2WCTM and it operates to supply feed-back energy to the rails of section 2T so that relay 2EH is picked up to establish the circuit for supplying energy from transformer 1WDT to relay 1WCTM and thus cause feed-back energy to be supplied to the rails of section 1T with the result that

70
75

relay 1EH is picked up and establishes the circuit of relay 1EHP.

It will be seen that when the stretch is conditioned for westbound traffic and is unoccupied, master code is supplied at the west end of the stretch and is also supplied to the west end of each track section to thereby cause the signal at the east end of the stretch to provide a permissive indication, while feed-back energy is supplied to the east end of the stretch and is cascaded through the stretch to maintain relay 1EHP at the west end of the stretch picked up. The relay 1EHP may be employed in any appropriate manner at this time to indicate that the single track stretch is unoccupied.

Operation of equipment on movement of a west-bound train through the track stretch

For purposes of illustration it will be assumed that with the equipment in the condition described above a westbound train accepts the permissive indication displayed by signal 3WS and enters the single track stretch.

When the train enters section ET, the track relay ETTR releases and its contact 42 interrupts the circuit traced above for supplying energy to the green lamp G of signal 3WS and establishes a circuit for supplying energy to the red lamp R of this signal.

In addition, on release of relay ETTR, its contact 46 interrupts the circuit for supplying energy from the decoding transformer 3WDT to relay 3WCTM and it ceases to supply feed-back energy to the rails of section 3T. Accordingly, relay 3ETR ceases to follow code and relay 3EH releases and its contact 53 interrupts the circuit for supplying energy from transformer 2WDT to relay 2WCTM and it ceases to supply feed-back energy to the rails of section 2T and relay 2ETR remains released with the result that relay 2EH releases. On release of relay 2EH its contact 35 interrupts the supply of energy from transformer 1WDT to relay 1WCTM and it ceases to supply feed-back energy to the rails of section 1T and relay 1ETR remains released with the result that relays 1EH and 1EHP release.

Accordingly, as soon as the westbound train enters section ET, the supply of feed-back energy to the section at the east end of the stretch is cut off with the result that the supply of feed-back energy to the other sections is also cut off, and the relay 1EHP at the west end of the stretch releases. The relay 1EHP may be employed at this time to provide an indication that the single track stretch is occupied.

When the supply of feed-back energy to section 3T is cut off and relay 3EH releases, its contact 54 establishes the circuit for supplying energy to the lamps of signal 2WS and energy is supplied to the green lamp G of signal 2WS over the circuit which includes front contact 55 of relay 2WSR, back contact 54 of relay 3EH, front contact 56 of relay 2WH, and front contact 57 of relay 3D.

Likewise, on release of relay 2EH, its contact 59 establishes the circuit for supplying energy to the lamps of the signal 1WS.

This system, therefore, operates so that the lamps of the intermediate signals are normally extinguished and so that on entrance of a train into the stretch the lamps of the signals for the established direction of traffic are lighted.

When the train advances into section 3T, relay 3WTR is shunted and remains released so that

energy is no longer supplied through the transformer 3WDT to the relays 3WH and 3WD and they release to maintain the supply of energy to the red lamp R of signal 3WS after section ET is vacated and relay ETTR picks up.

When the train enters section 2T, the relay 2WTR is shunted and remains released so that relays 2WH and 3D release. On release of relay 2WH, its contact 56 interrupts the circuit traced above for supplying energy to the green lamp G of signal 2WS and establishes the circuit of the red lamp R of this signal so that the signal now displays its red or stop indication.

In addition, when relay 2WH releases, its contact 60 interrupts the circuit for supplying energy of 120 code frequency to relay 3ECTM and establishes the circuit for supplying energy of 75 code frequency thereto. This circuit includes back contact 60 of relay 2WH, back contact 61 of relay 2WJ, front contact 62 of relay 2WSR, and back contact 63 of relay 3ESR. Accordingly, when section 3T is vacated, this energy feeds to relay 3WTR and operates it so that relay 3WHP is picked up but relay 3WD remains released. When relay 3WHP picks up, its contact 44 interrupts the circuit of the red lamp R of signal 3WS and establishes the circuit of the yellow or caution lamp Y of the signal 3WS.

When relay 3WHP picks up, its contact 47 establishes the circuit for supplying energy from a secondary winding of transformer 3WDT to relay 3WCTM and it operates to supply feed-back energy to the rails of section 3T and this energy operates relay 3ETR so that relay 3EH picks up. When relay 3EH picks up, its contact 54 interrupts the circuit for supplying energy to the lamps of signal 2WS and the lamps of this signal are extinguished which is proper since it is unnecessary for the signal lamps to be lighted when section 3T is not occupied.

In addition, when relay 3EH picks up, its contact 53 permits energy to be supplied from a secondary winding of transformer 2WDT to relay 2WCTM when section 2T is vacated and relay 2WTR is operated by coded energy.

When the train advances into section 1T, the relay 1WTR is shunted so energy is no longer supplied to relays 1WH and 2D and they release with the result that energy is supplied to the red lamp R of signal 1WS while the energy supplied to relay 2ECTM is changed from 120 to 75 code frequency.

When the train vacates section 2T, the relay 2WTR responds to the energy of 75 code frequency supplied to the section rails and relay 2WH picks up so that its contact 60 changes the energy supplied to relay 3ECTM from 75 to 120 code frequency, while contact 56 of relay 2WH interrupts the circuit of the red lamp R and establishes the circuit of the yellow lamp Y of signal 2WS with the result that signal 2WS, when lighted, displays its yellow or caution indication.

The energy of 120 code frequency supplied to the rails of section 3T operates the relay 3WTR at a rate such that relay 3WD picks up and its contact 45 interrupts the circuit of the yellow lamp Y and establishes the circuit of the green lamp G of signal 3WS.

In addition, when the train vacates section 2T and relay 2WTR follows coded energy, impulses of energy are supplied from the transformer 2WDT to relay 2WCTM and it causes feed-back energy to be supplied to the rails of section 2T and this energy operates relay 2ETR to pick up

relay 2EH. When relay 2EH picks up, its contact 59 interrupts the circuit for supplying energy to the lamps of signal 1WS, while contact 35 establishes the circuit for supplying energy from a secondary winding of transformer 1WDT to relay 1WCTM.

If, while the train under consideration is in section 1T, a second or following train should enter the stretch, the supply of feed-back energy over the rails of sections 3T and 2T will be cut off and relays 3EH and 2EH will release to cause the lamps of signals 2WS and 1WS to be lighted to thereby provide indications of traffic conditions in advance, while release of relays 3EH and 2EH prevents supply of feed-back energy to the sections in advance of the train and thus prevents picking up of relay 1EHP when the first train vacates section 1T.

When the first train enters section WT, the relay WTTR releases and its contact 14 changes the energy supplied to relay 1ECTM from 120 to 75 code frequency, while contact 16 of relay WTTR interrupts one circuit and establishes another circuit for supplying energy to the red lamp R of signal 1ES.

When the train vacates section 1T, the coded energy supplied to the section rails feeds to relay 1WTR and operates it so that relay 1WH picks up to change the energy supplied to relay 2ECTM from 75 to 120 code frequency, while contact 65 of relay 1WH interrupts the circuit of the red lamp R and establishes the circuit of the yellow lamp Y of signal 1WS so that the signal, when lighted, displays its caution indication.

The energy of 120 code frequency supplied to the rails of section 2T operates relay 2WTR at a rate such that relay 3D picks up to cause signal 2WS, when lighted, to display its clear indication, while relay 1WH remains picked up to maintain the supply of energy of 120 code frequency to the relay 3ECTM.

When the train under consideration vacates section 1T, and assuming that no other train has entered the single track stretch, energy is supplied from transformer 1WDT to relay 1WCTM and it operates to supply feed-back energy to the rails of section 1T and this energy operates relay 1ETR so that relay 1EHP picks up to provide an indication that the single track stretch is now unoccupied.

If, when the first train vacates section 1T, a second or following train has entered the single track stretch, the supply of feed-back energy over the rails of the sections in advance of the train is cut off and relay 1EHP remains released when section 1T is vacated.

From the foregoing, it will be seen that when the stretch is conditioned for westbound traffic and a westbound train enters the stretch, the supply of feed-back energy throughout the stretch in advance of the train is cut off to thereby cause the lamps of the wayside signals in advance of the train to be lighted, while relay 1EHP at the west end of the stretch releases to indicate that the stretch is occupied. In addition, it will be seen that as the train advances through the stretch feed-back energy is supplied to the sections in the rear of the train to extinguish the lamps of the wayside signals, while master code of appropriate code frequency is supplied to these sections to cause the wayside signals to provide the proper indications for a following train.

Operation of the equipment to condition stretch for eastbound traffic

When it is desired to prepare the stretch for eastbound traffic, a pick-up circuit is established for relay EMR. This circuit may be established by depressing the normally open push button EPB, or it may be established by other appropriate means, such as closing of the remotely controlled contact in the circuit of relay EMR. When relay EMR picks up, its contact 65 establishes a stick circuit including back contact 66 of relay 1ED to maintain relay EMR picked up until relay 1ED picks up.

When the stretch is conditioned for westbound traffic, relay WDR is picked up and its contact 68 interrupts the circuit of relay 1ED and the relay 1ED is released on picking up of relay EMR.

When relay EMR picks up, its contact 70 establishes the circuit including front contact 11 of relay 1EHP and back contact 12 of relay 1EJ for supplying energy to the relay EFR and the contacts of relay EFR pick up so that its contact 11 interrupts the stick circuit of relay WDR and its contacts release with the result that its contact 12 cuts off the supply of energy of 75 or 120 code frequency to the relay 1ECTM.

Since the circuit of relay EFR includes a front contact of relay 1EHP, and as relay 1EHP is picked up only when the single track stretch is unoccupied, energy will not be supplied to relay EFR on picking up of relay EMR at a time when the stretch is occupied. Under these conditions, relay EMR remains picked up, and as soon as the stretch is vacant and relay 1EHP is picked up, energy is supplied to relay EFR and it picks up to initiate the traffic reversing function.

When relay EFR picks up, its contact 14 interrupts the circuits controlled by relays 1EHP and 1ED for supplying energy to the lamps of signal 1ES and establishes a circuit for lighting the red lamp R of signal 1ES and thus insures that this signal will display its red or stop indication until the traffic reversing function is completed.

When relay WDR releases, its contact 161 interrupts the pick-up circuit of relay EMR while its contact 17 interrupts one circuit for supplying energy to the red lamp R of signal 1ES and establishes the circuit including front contact 74 of relay EFR for supplying energy to this signal lamp.

In addition, when relay EFR picks up, its contact 79 interrupts the circuit of relay 1EJ to insure that it remains released at this time.

When relay WDR releases and cuts off the supply of coded energy to relay 1ECTM, the supply of master code to the rails of section 1T is discontinued so relay 1WTR ceases to follow code and energy is no longer supplied from the transformer 1WDT to relay 1WCTM and it ceases to supply feed-back energy to the rails of section 1T so relay 1ETR remains released and relays 1EH and 1EHP release.

When relay 1EHP releases, its contact 11 interrupts the previously traced pick-up circuit for relay EFR and establishes a stick circuit to keep the relay picked up as long as relay EMR is picked up. The stick circuit for relay EFR includes its own front contact 13, back contact 11 of relay 1EHP, and front contact 70 of relay EMR, while relay EFR is slow enough in releasing to remain picked up during movement of contact 71 of relay 1EHP between its picked-up and released positions.

When the relay WDR releases and cuts off the supply of coded energy to the relay 1ECTM, the contacts of relay 1ECTM remain released and connect relay 1ETR across the section rails so that energy supplied over the section rails may pick up the contacts of relay 1ETR. When relay WDR is released, its contact 23 interrupts the circuit of the holding winding of relay 1ETR so that if the contacts of relay 1ETR pick up, they will release as soon as the supply of energy over the section rails is cut off. After relay 1ECTM ceases to supply master code energy to the rails of section 1T, an impulse of feed-back energy may be supplied over the section rails to pick up relay 1ETR, while on release of relay 1ETR an impulse of energy is induced in the secondary winding of transformer 1EDT which, if supplied to relay 1ECTM, would pick up its contacts and cause an impulse of energy to be supplied from the battery 1WTB to the section rails with the result that the equipment at the right-hand end of section 1T would operate to supply an impulse of feed-back energy to the section rails and relay 1ETR would pick up and release and cause relay 1ECTM to pick up and repeat the cycle just described. If this condition should develop, the coding operation of relay 1ETR would keep relay 1EHP picked up.

The possibility that the condition described above can occur is eliminated since, when relay 1EPR picks up, its contact 76 interrupts the circuit for supplying energy from the secondary winding of transformer 1EDT to relay 1ECTM. Accordingly, when relay WDR releases and cuts off the supply of coded energy to relay 1ECTM, the relay 1ETR remains released and relays 1EH and 1EHP are certain to release.

When relay 1EHP releases, its contact 77 interrupts the circuit for supplying energy from transformer 1EDT to relay 1ECTM and establishes the circuit for supplying energy of 180 code frequency to relay 1ECTM. This circuit includes a contact of a code transmitter 180CT, front contact 78 of relay 1EPR, back contact 77 of relay 1EHP, and back contact 12 of relay WDR, so the relay 1ECTM is operated at the 180 code rate and causes energy of 180 code frequency to be supplied to the rails of section 1T.

The energy of 180 code frequency supplied to the rails of section 1T operates relay 1WTR at a rate such that energy from transformer 1WDT picks up relay 1WJ, while when relay 1WJ picks up, its contact 80 establishes a circuit including front contact 86 of relay 1WH to supply energy to the holding winding of relay 1WJ and keep its contacts picked up as long as relay 1WH is picked up. When relay 1WJ picks up, its contact 81 interrupts the circuit of relay 2EJ to insure that it remains released, while contact 82 of relay 1WJ interrupts the circuit over which energy is supplied from a secondary winding of transformer 2EDT to relay 2ECTM. In addition, on picking up of relay 1WJ, its contact 34 interrupts the circuit for supplying energy from transformer 1WDT to relay 1WCTM and thus prevents operation of this relay to supply feed-back energy to the rails of section 1T.

Energy is supplied from transformer 1WDT to relay 1WCTM in the period from picking up of relay 1WH to picking up of relay 1WJ and this energy causes relay 1WCTM to supply feed-back energy to the rails of section 1T. This feed-back energy operates relay 1ETR, but does not do so long enough to pick up relays 1EH and 1EHP so relay 1EHP remains released and maintains the

supply of energy of 180 code frequency to relay 1ECTM.

When relay 1WJ picks up, its contact 39 interrupts the circuit for supplying energy of 75 or 120 code frequency to the relay 2ECTM and its contacts remain released so that master code is no longer supplied to the rails of section 2T while the equipment at the east end of the section ceases to supply feed-back energy to the section rails and relay 2ETR remains released and relay 2EH releases.

In addition, when relay 1WJ picks up, its contact 84 interrupts a circuit governed by a contact of relay 2ETR for at times supplying energy to relay 1WCTM, while contact 85 of relay 1WJ permits energy to be supplied to the pick-up circuit of relay 2ESR.

When relay 1WJ picks up, its contact 27 interrupts one stick circuit for relay 1WSR and establishes for relay 1WSR a stick circuit including front contact 59 of relay 2EH so that relay 1WSR remains picked up until relay 2EH releases.

When relay 2EH releases, its contact 59 interrupts the stick circuit for relay 1WSR established on picking up of relay 1WJ and the relay 1WSR releases with the result that its contact 26 additionally interrupts the relay stick circuits.

When relay 2EH releases, its contact 87 interrupts the circuit of relay 2ESR so that energy is not supplied to relay 2ESR on release of the contacts of relay 1WSR.

When relay 1WSR releases, a circuit governed by contact 83 of relay 1WTR is established for supplying energy to relay 2ECTM. This circuit is traced from back contact 88 of relay 1WTR, through an asymmetric unit 89, back contact 63 of relay 2EJ, back contact 49 of relay 1WSR, and back contact 41 of relay 2ESR so the relay 2ECTM operates at the same rate as the relay 1WTR, that is, at the 180 code rate. The asymmetric unit 89 included in the circuit just traced prevents the release time of relay 2ECTM being prolonged because of the snubbing effect of the primary winding of transformer 1WDT and thus insures that relay 2ECTM will operate to supply impulses of energy of proper length to the rails of section 2T.

In addition, when relay 1WSR releases, its contact 83 interrupts the circuit of the holding winding of relay 2ETR so that on subsequent code following operation of relay 2ETR energy is not supplied to this winding.

The energy of 180 code frequency supplied to the rails of section 2T operates relay 2WTR so that energy is supplied through transformer 2WDT to relays 2WH and 2WJ and their contacts pick up. If relay 2WH picks up prior to relay 2WJ, energy is supplied from a secondary winding of transformer 2WDT over front contact 91 of relay 2WH, back contact 93 of relay 2WJ, front contact 53 of relay 3EH, and front contact 94 of relay 2WSR to relay 2WCTM and it operates to supply feed-back energy to the rails of section 2T. Since the circuit for supplying energy to relay 2WCTM includes a front contact of relay 2WH, energy is not supplied to relay 2WCTM on code following operation of relay 2WTR until relay 2WH picks up, and the relay 2WH is of a type the contacts of which are slow to pick up so its contacts pick up little if any in advance of the contacts of relay 2WJ. Accordingly, if relay 2WCTM operates to supply any feed-back energy to the rails of section 2T at this time, it will only supply one or two impulses. This energy will operate relay 2ETR to supply energy to relay 2EH, but the relay 2EH is slow to pick up so it prob-

ably will not pick up at this time. If relay 2EH does pick up, it will establish the pick-up circuit for relay 2ESR as hereinafter explained, but relay 2ESR is of a type which is slow to pick up so it does not pick up within the period during which the contacts of relay 2EH are picked up at this time, if they do become picked up.

The arrangement just described insures that relay 2ESR remains released at this time so that its contact 41 maintains the circuit governed by contact 88 of relay 1WTR for supplying energy of 180 code frequency to relay 2ECTM.

When relay 2WJ picks up, its contact 93 interrupts the circuit for supplying energy from transformer 2WDT to relay 2WCTM and its contacts remain released and do not cause feed-back energy to be supplied to the rails of section 2T.

When relay 2WJ picks up, its contact 95 establishes a circuit including front contact 96 of relay 2WH for supplying energy to the holding winding of relay 2WJ and keeps its contacts picked up as long as relay 2WH is picked up.

Also when relay 2WJ picks up, its contact 97 interrupts the circuit including a back contact of relay 3ETR for supplying energy to relay 2WCTM, and thus insures that relay 2WCTM will remain released after release of relay 2WSR and prior to picking up of relay 3ESR.

In addition, when relay 2WJ picks up, its contact 64 interrupts the circuit for supplying energy of 75 or 120 code frequency to the relay 3ECTM and it ceases to supply master code to the rails of section 3T so the equipment at the right-hand end of section 3T ceases to supply feed-back energy to the section rails and relay 3ETR ceases to follow code and relay 3EH releases. At this time, the relays 3WH, 3WHP and 3WD release to cause the signal 3WS to display its red or stop indication and thus prevent a westbound train from entering the track stretch.

On picking up of relay 2WJ, its contact 99 interrupts one stick circuit for relay 2WSR and establishes for relay 2WSR a stick circuit which includes front contact 54 of relay 3EH so relay 2WSR remains picked up until relay 3EH releases, whereupon relay 2WSR releases and its contact 55 interrupts the relay stick circuits.

When relay 2WSR releases, coded energy is supplied to relay 3ECTM over the circuit which is traced from back contact 100 of relay 2WTR, asymmetric unit 101, back contact 102 of relay 3EJ, back contact 62 of relay 2WSR, and back contact 63 of relay 3ESR so the relay 3ECTM is operated at the same code rate as the relay 2WTR, that is, at the 180 code rate. As shown, energy is supplied to relay 3ECTM over the back contact of relay 2WTR, but it is obvious that, if desirable or necessary to correct for code distortion, the relay 3ECTM might be energized over a front contact of track relay 2WTR, while the corresponding circuits for either direction of traffic at other points in the track stretch may be controlled by either a front or a back contact of a track relay.

When relay 3ECTM operates at the 180 code rate, energy of this code frequency is supplied to the rails of section 3T and operates relay 3WTR at a rate such that energy is supplied, through the transformer 3WDT to pick up relay 3WJ. The circuit for supplying energy to relay 3WJ includes back contact 105 of relay WFR and as relay WFR is released at this time energy is supplied to relay 3WJ.

When relay 3WJ picks up, its contact 104 in-

5 sure that it remains released and thereby makes ineffective an attempt to prepare the stretch for westbound traffic before the equipment completes its operation to prepare the stretch for eastbound traffic.

When relay 3WJ picks up, its contact 103 interrupts the circuit for supplying energy from transformer 3WDT to relay 3WCTM, while its contact 106 establishes the pick-up circuit of relay EDR and its contacts pick up with the result that its contact 48 additionally interrupts the circuit for supplying energy from transformer 3WDT to relay 3WCTM and establishes the circuit for supplying to relay 3WCTM energy of 75 or 120 code frequency depending on traffic conditions at the right of section 3T.

In addition, on picking up of relay EDR, its contact 43 interrupts the circuits controlled by relays 3WHP and 3WD for supplying energy to the lamps of signal 3WS and establishes the circuit of the red or stop lamp R of this signal, while contact 107 of relay EDR establishes for the relay EDR a stick circuit which includes back contact 108 of relay WFR. This stick circuit maintains relay EDR picked up after relay 3WJ releases and causes relay EDR to remain picked up until relay WFR is picked up to condition the stretch for westbound traffic.

When relay EDR is picked up, its contact 109 permits energy to be supplied to the holding winding of relay 3WTR so that on operation of relay 3WTR by feed-back energy the relay contacts will be maintained picked up for the entire released periods of relay 3WCTM.

When relay 3WTR is operated by energy of 180 code frequency, energy is supplied through the transformer 3WDT to relay 3WH as well as to relay 3WJ and the relay 3WH may pick up prior to picking up of relay 3WJ. If this occurs, energy is supplied from the transformer 3WDT to relay 3WCTM in the interval from picking up of relay 3WH to picking up of relay 3WJ and the relay 3WCTM will operate to supply feed-back energy to the rails of section 3T. However, as explained in connection with section 2T, these impulses of feed-back energy will be too few in number to pick up relay 3ESR so it remains released and maintains the supply of energy of 180 code frequency to relay 3ECTM.

After relay EDR picks up, the relay 3WCTM is operated by coded energy of 75 or 120 code frequency and causes energy of this code frequency to be supplied to the rails of section 3T. At this time, relay 3ECTM is being operated at the 180 code rate, and because of the difference in the rates of operation of the relays 3WCTM and 3ECTM there are frequently recurring periods during which impulses of energy supplied from battery 3ETB to the section rails feed over the back contact of relay 3ECTM and pick up the contacts of the relay 3ETR. Furthermore, because of the difference in the code speeds energy will be supplied to relay 3ETR during several successive released periods of the relay 3ECTM and the relay 3ETR will be operated several times in quick succession with the result that sufficient energy is supplied through the transformer 3EDT to relay 3EH to pick it up and keep it picked up until relay 3ESR picks up.

When relay 3EH picks up, it establishes the pick-up circuit of relay 3ESR. This circuit includes back contact 55 of relay 2WSR, front contact 112 of relay 2WJ, front contact 114 of relay 3EH, and back contact 115 of relay 3EJ. When relay 3ESR picks up, its contact 116 establishes

a stick circuit for the relay including back contact 115 of relay 3EJ so that relay 3ESR remains picked up until relay 3EJ is picked up which occurs only when the stretch is being conditioned for westbound traffic.

When relay 3ESR picks up, its contact 63 interrupts the circuit governed by contact 100 of relay 2WTR for supplying coded energy to relay 3ECTM, and connects relay 3ECTM to the circuit over which energy is supplied from transformer 3EDT. However, at this time, this circuit is interrupted by contact 118 of relay 2WJ so on picking up of relay 3ESR the relay 3ECTM remains released and ceases to cause energy to be supplied to the rails of section 3T, while the relay 2ETR is constantly connected across the section rails and accurately follows the coded energy supplied to the section rails. Accordingly, relay 3EH remains picked up, while relay 2D will pick up if the energy supplied to the rails of section 3T is coded at the 120 code rate. When relay 3ESR picks up, the relay 3D is connected to the transformer 3EDT over a circuit controlled by front contacts 121 and 122 of relay 3ESR and by back contacts 124 and 125 of relay 2WSR.

When relay 3ECTM ceases to supply energy to section 3T, the relay 3WTR remains released and relay 3WH releases, and relay 3WJ also releases if it has not already released because of irregular operation of relay 3WTR after relay 3WCTM is operated by energy of 75 or 120 code frequency. When relay 3WJ releases, its contact 106 interrupts the pick-up circuit of relay EDR but this relay is maintained picked up by energy supplied over its stick circuit and therefore maintains the supply of coded energy to relay 3WCTM. In addition, on release of relay 3WJ its back contact 103 is closed but as relay EDR is picked up energy cannot be supplied from transformer 3WDT to relay 3WCTM.

On release of relay 3WH, relay 3WHP releases and its contact 127 interrupts the pick-up circuit of relay WFR to thereby prevent picking up of this relay and thus renders ineffective an attempt to prepare the stretch for westbound traffic until operation of the equipment to prepare the stretch for eastbound traffic is complete.

When relay 3ESR picks up, energy of 120 code frequency is supplied to relay 2WCTM over the circuit which includes front contact 130 of relay 3EH, back contact 131 of relay 3EJ, front contact 132 of relay 3ESR, and back contact 94 of relay 2WSR so the relay 2WCTM operates to supply energy of 120 code frequency to the rails of section 2T.

When relay 3WSR picks up, its contact 63 connects relay 3ECTM to the circuit over which energy is supplied from a secondary winding of transformer 3EDT, but as long as relay 2WJ is picked up its contact 118 interrupts this circuit and prevents supply of energy to the relay 3ECTM. As explained above, when relay 2WJ picks up, it establishes for itself a stick circuit including front contact 96 of relay 2WH. Accordingly, when relay 2WCTM is operated by coded energy and operation of relay 2WTR becomes irregular, relay 2WJ is maintained picked up by energy supplied to its holding winding, and contact 118 of relay 2WJ prevents the supply of energy from transformer 3EDT to relay 3ECTM and relay 3ECTM does not operate to supply feed-back energy to the rails of section 3T and relays 3WH and 3WHP remain released.

5 The energy of 120 code frequency supplied to the rails of section 2T as a result of operation of relay 2WCTM feeds to relay 2ETR during released periods of relay 2ECTM and operates relay 2ETR so that relay 2EH picks up and establishes the pick-up circuit for relay 2ESR. When relay 2EH picks up, energy is supplied to relay 2ESR over the circuit which includes back contact 26 of relay 1WSR, front contact 85 of relay 1WJ, front contact 87 of relay 2EH, and back contact 133 of relay 2EJ, while when relay 2ESR picks up, its contact 134 establishes a stick circuit including back contact 133 of relay 2EJ to maintain the relay picked up until relay 2EJ is picked up.

10 When relay 2ESR picks up, the relay 2D is connected over back contacts 29 and 32 of relay 1WSR and front contacts 30 and 31 of relay 2ESR to the transformer 2EDT, and as relay 2ETR is operated at the 120 code rate the contacts of relay 2D pick up.

15 When relay 2ESR picks up, its contact 41 interrupts the circuit including back contact 88 of relay 1WTR for supplying energy to relay 2ECTM and connects relay 2ECTM to the circuit over which energy is supplied from transformer 2EDT to relay 2ECTM. However, on picking up of relay 2ESR, the circuit leading from transformer 2EDT is interrupted by contact 82 of relay 1WJ so 20 energy is not supplied to relay 2ECTM and it remains released and does not supply energy to the rails of section 2T. Accordingly, relay 2WTR remains released and relay 2WH releases with the result that its contact 135 prevents supply of 25 energy from transformer 3EDT to relay 3ECTM and it remains released. In addition, on release of relay 2WH its contact 96 interrupts the stick circuit for relay 2WJ and its contacts release, but contact 135 of relay 2WH interrupts the circuit 30 for supplying energy from transformer 2EDT to relay 3ECTM before contact 118 of relay 2WJ establishes this circuit so relay 3ECTM remains released. As a result relays 3WH and 3WHP remain released and contact 127 of relay 3WHP 35 interrupts the pick-up circuit of relay WFR to thereby render ineffective an attempt to prepare the stretch for westbound traffic before the equipment completes its operation to prepare the stretch for east-bound traffic.

40 When relay 2ESR picks up, the circuit for supplying traffic governing coded energy to relay 1WCTM is established and includes a contact of code transmitter 120CT, front contact 140 of relay 2EH, back contact 141 of relay 2EJ, front contact 142 of relay 2ESR, and back contact 36 of relay 1WSR. Accordingly, relay 1WCTM operates to supply energy of 120 code frequency to the rails of section 1T and this energy feeds to relay 1ETR during the released periods of relay 1ECTM so 45 that energy is supplied through the transformer 1EDT to the relay 1EH and it picks up to establish the circuit of relay 1EHP and the contacts of relay 1EHP pick up with the result that contact 71 50 interrupts the supply of energy of 180 code frequency to the relay 1ECTM and connects relay 1ECTM to the circuit over which energy is supplied from a secondary winding of transformer 1EDT. However, at this time this circuit is interrupted by contact 76 of relay EFR so that on 55 picking up of relay 1EHP the relay 1ECTM is not operated by energy supplied from transformer 1EDT, but remains released and constantly connects relay 1ETR across the section rails. Accordingly, relay 1ETR will accurately follow the 60 energy of 120 code frequency supplied over the 65

rails of section 1T and energy is supplied through the transformer 1EDT and the resonant rectifier unit 120DU to the relay 1ED and its contacts pick up with the result that contact 66 interrupts the stick circuit for relay EMR and its contacts release so that contact 65 additionally interrupts the relay stick circuit.

When relay 1EHP picks up, its contact 71 transfers control of relay EFR from its stick circuit to its pick-up circuit, while on release of relay EMR its contact 70 interrupts the pick-up circuit of relay EFR and its contacts release so that contact 73 interrupts the relay stick circuit and contact 78 interrupts the circuit over which energy of 180 code frequency was supplied to relay 1ECTM.

In addition, when relay EFR releases, its contact 74 interrupts the circuit of the red lamp R of signal 1ES and establishes the circuit controlled by relays 1EHP and 1ED for supplying energy to the lamps of signal 1ES. At this time relays 1EHP and 1ED are picked up so energy is supplied over front contact 16 of relay WTTR, back contact 17 of relay WDR, back contact 74 of relay EFR, front contact 144 of relay 1EHP, and front contact 145 of relay 1ED to the green lamp G of signal 1ES and this signal therefore provides a green or clear indication to indicate that the single track stretch is conditioned for eastbound traffic. It will be seen, therefore, that when the established direction of traffic is changed from eastbound to westbound the signal 1ES governing entrance of eastbound trains into the track stretch is caused to display its red or stop indication during operation of the equipment to change the direction of traffic and that when the traffic reversing function is completed the signal 1ES displays an indication controlled by traffic in advance.

When relay EFR releases, its contact 79 establishes the circuit of relay 1EJ to permit the equipment to be operated to condition the stretch for westbound traffic, while contact 76 establishes the circuit for supplying energy from transformer 1EDT to relay 1ECTM. This circuit includes front contact 146 of relay WTTR, back contact 16 of relay EFR, back contact 147 of relay 1EJ, front contact 71 of relay 1EHP, and back contact 12 of relay WDR. Accordingly, the relay 1ECTM now operates to supply impulses of feed-back energy to the rails of section 1T.

It will be seen that operation of relay 1ECTM to supply energy of 180 code frequency to the rails of section 1T is discontinued when relay 1EHP picks up, while operation of relay 1ECTM to supply feed-back energy to the section rails is not initiated until relay EFR releases, and release of relay EFR is not initiated until relay EMR releases, while release of relay EMR is not initiated until relay 1ED picks up. Accordingly, there is a considerable period from the time relay 1ECTM ceases to supply energy of 180 code frequency to the rails of section 1T and the time at which it starts to operate to supply feed-back energy to the section rails. This period is long enough to insure that relays 1WJ and 1WH will release to interrupt the circuit of the holding winding of relay 1WJ so that the contacts of relay 1WJ are released.

On operation of relay 1ECTM to supply feed-back energy to the rails of section 1T, relay 1WTR is operated and energy is supplied through transformer 1WDT to pick up relay 1WH. At this time, contact 148 of relay 2ESR establishes the circuit for supplying energy to the holding winding of relay 1WTR to thereby cause the con-

5 tacts of relay 1WTR, when picked up, to remain picked up for the entire released period of the contacts of relay 1WCTM.

When relay 1WH picks up, energy is supplied from transformer 2EDT to relay 2ECTM over the circuit which includes front contact 150 or relay 2EH, back contact 151 of relay 2EJ, back contact 82 of relay 1WJ, front contact 152 of relay 1WH, and front contact 41 of relay 2ESR. Accordingly, relay 2ECTM operates to supply feed-back energy to the rails of section 2T and this energy operates relay 2WTR to pick up relay 2WH, while on picking up of relay 2WH energy is supplied from transformer 3EDT to relay 3ECTM over a circuit similar to that just traced for relay 2ECTM, and relay 3ECTM operates to supply feed-back energy to the rails of section 3T. This energy operates relay 3WTR to pick up relay 3WH and thus pick-up relay 3WHP, while 10 on picking up of relay 3WHP suitable means, not shown, may be operated to indicate that the track stretch is unoccupied, while this indication may also serve as an indication that the traffic reversing function is complete and that 15 the stretch is prepared for eastbound traffic.

When the traffic reversing function is completed, relays 1WH and 2WH are picked up so energy is not supplied to the lamps of signals 2ES and 3ES and these signals are dark at this time which 20 is proper since the stretch is vacant and there is no need for the signals to be lighted.

The operation of the equipment to change the stretch from eastbound to westbound traffic is similar to that just traced for changing from 25 westbound to eastbound traffic and a detailed explanation of the operation of the equipment at these times is unnecessary.

If, after the stretch has been prepared for 30 eastbound traffic, an eastbound train accepts the permissible indication displayed by signal 1ES and enters the single track stretch, relay WTTR will release so that its contact 16 cuts off the supply of energy to the green lamp G of signal 1ES and establishes the circuit of the red lamp R of this signal. In addition, on release of relay WTTR its contact 146 interrupts the circuit for supplying energy from transformer 1EDT to relay 1ECTM and it ceases to supply feed-back energy to the rails of section 1T. Accordingly, 35 relay 1WTR remains released and relay 1WH releases with the result that energy is supplied to the green lamp G of signal 2ES over the circuit which includes front contact 134 of relay 2ESR, back contact 155 of relay 1WH, front contact 153 of relay 2EH, and front contact 154 of relay 2D so that the signal 2ES displays its green or clear indication.

On release of relay 1WH its contact 152 40 interrupts the circuit for supplying energy from transformer 2EDT to relay 2ECTM and it ceases to supply feed-back energy to the rails of section 2T and relay 2WH releases to establish the circuit for supplying energy to the lamps of signal 3ES, and to interrupt the supply of energy from transformer 3EDT to relay 3ECTM. Accordingly, relay 3ECTM remains released and ceases to supply feed-back energy to the rails of section 3T so that relay 3WTR ceases to follow code and 45 relays 3WH and 3WHP release to prevent picking up of relay WFR and thus render ineffective an attempt to change the established direction of traffic. If desired, release of relay 3WHP may be employed to indicate that the single track stretch is occupied.

50 55 60 65 70 75 As the eastbound train proceeds through the

track stretch the equipment operates in a manner similar to that described in connection with movement of a westbound train through the track stretch and a detailed description of the operation of the equipment is unnecessary. As each section is vacated by the eastbound train, feed-back energy is supplied over the section rails to operate the equipment at the exit end of the section to extinguish the lamps of the wayside signal for the adjacent section in advance and to condition the equipment for the section in advance to operate to supply feed-back energy over the section rails when that section is vacated. As soon as the train vacates section 3T, relays 3WH and 3WHP pick up to permit energy to be supplied to relay WFR and thus permit the established direction of traffic to be reversed if desired.

It will be seen that the supply of feed-back energy to the stretch is cut off as soon as a train passes the headblock signal and enters the detector section at the existing entrance end of the stretch so that the equipment at the exit end of the stretch operates immediately to indicate that the stretch is occupied and to prevent interruption with the established direction of traffic.

It will be seen also that reversal of the established direction of traffic may be initiated while the detector section at the exit end of the stretch is occupied. Accordingly, on movement of a train in one direction through the stretch, the change in the established direction of traffic may be effected with a minimum of delay. While a change in the established direction of traffic can be initiated before the detector section is vacated, the headblock signal governing entrance of trains into the track stretch at the new entrance end will not display a permissive indication until the detector section is vacated since this signal is controlled by the track relay of the detector section. This prevents clearing of the headblock signal even though operation of the equipment to reverse the established direction of traffic should be completed before the detector section is vacated.

This system is arranged so that when the stretch is conditioned for either direction of traffic, depressing of the push button at the existing entrance end of the stretch has no effect. When the stretch is conditioned for westbound traffic, the relay EDR is released and its contact 160 interrupts the pick-up circuit for relay WMR so that, if the push button WPB should be depressed or the associated remotely controlled contact be closed, it would have no effect and relay WMR would remain released, while the equipment would continue to function in the normal manner. Similarly, when the stretch is conditioned for eastbound traffic, relay WDR is released and its contact 161 interrupts the pick-up circuit of relay EMR so that, if the push button EPB should be depressed, the relay EMR will remain released and the equipment will continue to function in the normal manner.

As explained above, when the established direction of traffic is to be changed, the supply of traffic governing energy of 75 or 120 code frequency to the section at the existing exit end of the stretch is cut off and energy of 180 code frequency is substituted therefor. In addition, as explained above, when the stretch is occupied, the supply of feed-back energy over the rails of the sections in advance of the train is discontinued and the equipment at the exit end of the

stretch operates to prevent the supply of energy of 180 code frequency to the stretch and thus renders ineffective an attempt to reverse the established direction of traffic.

However, if for any reason the equipment is not functioning as intended and traffic reversing energy of 180 code frequency should be supplied to the exit end of the stretch when the stretch is occupied, it would not condition the stretch for movement of traffic in the direction opposite to that of the train present in the stretch and, therefore, would not create a hazardous condition.

For purposes of illustration, it will be assumed that the stretch is conditioned for westbound traffic and that a westbound train has entered the stretch and is present in section 3T. As the stretch is assumed to be prepared for westbound traffic, the westbound directional stick relays 1WSR and 2WSR are picked up, while relay WDR is also picked up. As section 3T is assumed to be occupied, the supply of feed-back energy over the rails of sections 2T and 1T is cut off and relays 1EH and 1EHP are released. Under these conditions, contact 71 of relay 1EHP interrupts the pick-up circuit for relay EFR and relay EFR should remain released to maintain the stick circuit for relay WDR and interrupt the circuit for supplying energy of 180 code frequency to relay 1ECTM.

If, as a result of some defect in the equipment, relay EFR should become picked up, its contact 12 will interrupt the stick circuit of relay WDR and its contacts will release and energy of 180 code frequency may be supplied to the relay 1ECTM with resultant supply of energy of this code frequency to relay 1WTR so that relay 1WJ picks up.

When relay 1WJ picks up, its contact 39 cuts off the supply of traffic governing coded energy to relay 2ECTM and thus causes it to cease to supply energy to the rails of section 2T so that the equipment at the right-hand end of section 2T causes the signal 2WS to display its stop indication, while the supply of feed-back energy over the rails of section 2T is cut off if it has not already been discontinued. Accordingly, relay 2EH releases and its contact 59 interrupts the stick circuit of relay 1WSR and it releases so that relay 2ECTM is operated by energy supplied over back contact 88 of relay 1WTR and energy of 180 code frequency is now supplied to the rails of section 2T. This energy operates relay 2WTR to pick up relay 2WJ and thus cause release of relay 2WSR so that its contact 55 interrupts the circuit of the lamps of signal 2WS, while relay 3ECTM is operated by energy supplied over back contact 100 of relay 2WTR.

As section 3T is assumed to be occupied, operation of relay 3ECTM is without effect and relay 3EH remains released and does not establish the pick-up circuit for relay 3ESR. Accordingly, relay 3ESR remains released and its contact 132 does not establish the circuit for supplying coded energy to relay 2WCTM so it remains released and coded energy is not supplied to the east end of section 2T so relay 2ESR remains released and does not establish the circuit for supplying coded energy to relay 1WCTM. Coded energy, therefore, is not supplied to the rails of section 1T and relays 1EH and 1EHP remain released to maintain the supply of energy of 180 code frequency to relay 1ECTM and to prevent the display of a permissive indication by signal 1ES.

It will be seen, therefore, that if energy of

180 code frequency should be supplied to the exit end of the stretch when the stretch is occupied, it will not cause the equipment to authorize entrance into the stretch of a train moving in the opposite direction to that already present in the stretch. Furthermore, the energy of 180 code frequency supplied to the stretch while it is occupied causes release of the directional stick relays for the established direction of traffic, thereby discontinuing the display of permissive indications by the signals governing movement of the train present in the track stretch. The absence of indications by the wayside signals will cause the train in the stretch to stop or to proceed at reduced speed, which is proper when the equipment is not functioning as intended.

The equipment operates in a similar manner if, while the stretch is conditioned for eastbound traffic and is occupied, energy of 180 code frequency is supplied to the east end of the stretch and a detailed explanation of the operation of the equipment is unnecessary.

It will be seen also that the normal operation of the equipment is such that, when the stretch is conditioned for either direction of traffic, the appropriate directional stick relays are picked up to maintain this direction of traffic, while the stick circuits for these relays are interrupted only on supply of the special traffic reversing code through the track stretch. This prevents interference with the established direction of traffic by unusual conditions such as temporary shunting of the rails of a track section at an intermediate point in the track stretch.

In addition, it will be seen that the system is arranged so that once the traffic reversing energy of 180 code frequency is supplied to the stretch, the supply of this energy is maintained and cannot be interrupted until the traffic reversing function is complete so there is no possibility that the established direction of traffic will be disturbed without the new direction of traffic being established.

Furthermore, the system is arranged so that establishment of the new direction of traffic is not begun until the special traffic reversing energy has been transmitted throughout the entire stretch so there is no possibility that the new direction of traffic will be established in a part of the stretch without being established in the entire stretch.

Modification shown in Fig. 2

As explained above, the system shown in Fig. 1 is arranged so that when the stretch is conditioned for westbound traffic the relay EMR may be picked up regardless of whether the stretch is occupied or not. If the stretch is vacant when relay EMR picks up, reversal of the established direction of traffic is initiated immediately. However, if, when relay EMR picks up, the stretch is occupied, the relay EMR is held picked up by its stick circuit and reversal of the direction of traffic is initiated as soon as the stretch is vacated.

This storage of control of traffic direction may not be desired, while, if it is not desired, it may be eliminated by including a front contact of relay 1EHP in the pick-up circuits of relay EMR, as shown in Fig. 2, to thereby prevent picking up of relay EMR when the stretch is occupied. Obviously, a front contact of relay 3WHP may be included in the pick-up circuit of relay WMR to prevent picking up of relay WMR when the stretch is occupied by an eastbound train.

The operation of the modification shown in

Fig. 2, therefore, is such that, if traffic conditions prevent reversal of the established traffic direction at the time the reversal is attempted, the reversal will not take place without further attention from an operator when traffic conditions change so that it is permissible.

Although I have herein shown and described only one form of railway signaling system embodying my invention, together with a modification thereof which I may employ, it is understood that various changes and modifications may be made therein within the scope of the appended claims without departing from the spirit and scope of my invention.

Having thus described my invention, what I claim is:

1. In combination, a stretch of single track railway through which traffic may move in either direction, the rails of said stretch being divided into a plurality of track sections, two sets of coded track circuit apparatus for each section, one for each direction of traffic, each set comprising a code following relay located at the corresponding entrance end of the section responsive to coded energy supplied over the track rails from the other end of the section, traffic direction control means effective at times to cause traffic in each section to be controlled by said coded track circuit apparatus for one direction of traffic and effective at other times to cause traffic in the section to be controlled by said coded track circuit apparatus for the other direction of traffic, means effective when the direction of traffic in the stretch has been established to supply to the corresponding exit end of each section energy of a traffic governing code frequency, means at each end of the stretch for controlling the direction of traffic movements through the stretch comprising means for cutting off the supply of energy of traffic governing code frequency to the rails of the section at that end of the stretch and for supplying thereto traffic reversing energy of a distinctive code frequency, means responsive to traffic reversing energy supplied to the track rails at the end of the stretch for causing energy of this code frequency to be supplied successively to the corresponding ends of the remaining sections of the stretch, means responsive to the supply of said traffic reversing energy over the rails of each section for causing the traffic direction control means to cancel the established direction of traffic in such section, means at each end of the track stretch responsive to the traffic reversing energy supplied from the opposite end of the stretch for causing traffic governing energy to be supplied to the rails of the section at that end of the stretch, means responsive to such traffic governing energy supplied to the rails at said end of the stretch for progressively cutting off the supply of traffic reversing energy to the successive sections in said stretch and for causing the supply of traffic governing energy to be repeated through the successive sections to the end of the stretch and including means responsive to the supply of traffic governing energy over the rails of each section for causing the traffic direction control means to establish the new direction of traffic in such section, and means at each end of the stretch responsive to the traffic governing energy supplied over the rails of the stretch to discontinue the supply of traffic reversing energy thereto.
2. In combination, a stretch of single track railway through which traffic may move in either direction, the rails of said stretch being divided into a plurality of track sections, two sets of

coded track circuit apparatus for each section, one for each direction of traffic, each set comprising a code following relay located at the corresponding entrance end of the section responsive to coded energy supplied over the track rails from the other end of the section, traffic direction control means comprising a first and a second stick relay at each junction between sections in said stretch, said traffic direction control means being effective when said first stick relays are picked up and said second stick relays are released to cause traffic in each section to be controlled by said coded track circuit apparatus for one direction of traffic and being effective when said first stick relays are released and said second stick relays are picked up to cause traffic in each section to be controlled by said coded track circuit apparatus for the other direction of traffic, means effective when the direction of traffic in the stretch has been established to supply to the corresponding exit end of each section energy of a traffic governing code frequency, means at each end of the stretch for controlling the direction of traffic movements through the stretch comprising means for cutting off the supply of energy of traffic governing code frequency to the rails of the section at that end of the stretch and for supplying thereto traffic reversing energy of a distinctive code frequency, means responsive to traffic reversing energy supplied to the track rails at the end of the stretch for causing the energized directional stick relays to release successively to thereby cancel the established direction of traffic and to cause energy of this code frequency to be supplied to the corresponding ends of the remaining sections of the stretch, means at each end of the track stretch responsive to the traffic reversing energy supplied from the opposite end of the stretch for causing traffic governing energy to be supplied to the rails of the section at that end of the stretch, means responsive to such traffic governing energy supplied to the rails at said end of the stretch for progressively picking up the directional stick relays which establish the new direction of traffic to thereby cut off the supply of traffic reversing energy to the successive sections in said stretch and to cause the supply of traffic governing energy to be repeated through the successive sections to the end of the stretch, and means at each end of the stretch responsive to the traffic governing energy supplied over the rails of the stretch to discontinue the supply of traffic reversing energy thereto and for controlling a signal governing entrance of traffic into the stretch.

3. In combination, a stretch of single track railway through which traffic may move in either direction, the rails of said stretch being divided into a plurality of track sections, two sets of coded track circuit apparatus for each section, one for each direction of traffic, each set comprising a code following relay located at the corresponding entrance end of the section responsive to coded energy supplied over the track rails from the other end of the section, traffic direction control means effective at times to cause traffic in each section to be controlled by said coded track circuit apparatus for one direction of traffic and effective at other times to cause traffic in the section to be controlled by said coded track circuit apparatus for the other direction of traffic, means effective when the direction of traffic in the stretch has been established to supply to the corresponding exit end of each section energy of a traffic governing code frequency, means at

each end of the stretch for controlling the direction of traffic movements through the stretch comprising means for cutting off the supply of energy of traffic governing code frequency to the rails of the section at that end of the stretch and for supplying thereto traffic reversing energy of a distinctive code frequency, means responsive to traffic reversing energy supplied to the track rails at the end of the stretch for causing energy of this code frequency to be supplied successively to the corresponding ends of the remaining sections of the stretch, means responsive to the supply of traffic reversing energy over the rails of each section for causing the traffic direction control means to cancel the established direction of traffic in such section, means at each end of the track stretch responsive to the traffic reversing energy supplied from the opposite end of the stretch for causing traffic governing energy to be supplied to the rails of the section at that end of the stretch, means responsive to such traffic governing energy supplied to the rails at said end of the stretch for progressively cutting off the supply of traffic reversing energy to the successive sections in said stretch and for causing the supply of traffic governing energy to be repeated through the successive sections to the end of the stretch and including means responsive to the supply of traffic governing energy over the rails of each section for causing the traffic direction control means to establish the new direction of traffic in such section, means at each end of the stretch responsive to the traffic governing energy supplied over the rails of the stretch to discontinue the supply of traffic reversing energy thereto, and means at each end of the stretch governed by traffic in the stretch for preventing interruption of the supply of traffic governing energy to the rails of the stretch at that end of the stretch while the stretch is occupied.

4. In combination, a stretch of single track railway through which traffic may move in either direction, the rails of said stretch being divided into a plurality of track sections, two sets of coded track circuit apparatus for each section, one for each direction of traffic, each set comprising a code following relay located at the corresponding entrance end of the section responsive to coded energy supplied over the track rails from the other end of the section, traffic direction control means effective at times to cause traffic in each section to be controlled by said coded track circuit apparatus for one direction of traffic and effective at other times to cause traffic in the section to be controlled by said coded track circuit apparatus for the other direction of traffic, means effective when the direction of traffic in the stretch has been established to supply to the corresponding exit end of each section master code energy of a traffic governing code frequency and to supply impulses of feed-back energy to the track rails entrance end of the track stretch, means responsive to feed-back energy supplied to the track rails at the entrance end of the stretch for causing feed-back energy to be supplied successively to the entrance end of the remaining sections of the stretch, means at each end of the stretch for controlling the direction of traffic movements through the stretch comprising means for cutting off the supply of energy of traffic governing code frequency to the rails of the section at that end of the stretch and for supplying thereto traffic reversing energy of a distinctive code frequency, means responsive to

traffic reversing energy supplied to the track rails at the end of the stretch for causing energy of this code frequency to be supplied successively to the corresponding ends of the remaining sections of the stretch, means responsive to the supply of said traffic reversing energy over the rails of each section for causing the traffic direction control means to cancel the established direction of traffic in such section, means at each end of the track stretch responsive to the traffic reversing energy supplied from the opposite end of the stretch for causing traffic governing energy to be supplied to the rails of the section at that end of the stretch, means responsive to such traffic governing energy supplied to the rails at said end of the stretch for progressively cutting off the supply of traffic reversing energy to the successive sections in said stretch and for causing the supply of traffic governing energy to be repeated through the successive sections to the end of the stretch and including means responsive to the supply of traffic governing energy over the rails of each section for causing the traffic direction control means to establish the new direction of traffic in such section, and means at each end of the stretch responsive to the traffic governing energy supplied over the rails of the stretch to discontinue the supply of traffic reversing energy thereto.

5. In combination, a stretch of single track railway through which traffic may move in either direction, the rails of said stretch being divided into a plurality of track sections, two sets of coded track circuit apparatus for each section, one for each direction of traffic, each set comprising a code following relay located at the corresponding entrance end of the section responsive to coded energy supplied over the track rails from the other end of the section, traffic direction control means effective at times to cause traffic in each section to be controlled by said coded track circuit apparatus for one direction of traffic and effective at other times to cause traffic in the section to be controlled by said coded track circuit apparatus for the other direction of traffic, means effective when the direction of traffic in the stretch has been established to supply to the corresponding exit end of each section master code energy of a traffic governing code frequency and to supply impulses of feed-back energy to the track rails entrance end of the track stretch, means responsive to feed-back energy supplied to the track rails at the entrance end of the stretch for causing feed-back energy to be supplied successively to the entrance end of the remaining sections of the stretch, means at each end of the stretch for controlling the direction of traffic movements through the stretch comprising means effective only when feed-back energy is being received over the track rails at that end of the stretch for cutting off the supply of energy of traffic governing code frequency to the rails of the section at that end of the stretch and for supplying thereto traffic reversing energy of a distinctive code frequency, means responsive to traffic reversing energy supplied to the track rails at the end of the stretch for causing energy of this code frequency to be supplied successively to the corresponding ends of the remaining sections of the stretch, means responsive to the supply of said traffic reversing energy over the rails of each section for causing the traffic direction control means to cancel the established direction

10 15 20 25 30 35 40 45 50 55 60 65 70 75

of traffic in such section, means at each end of the track stretch responsive to the traffic reversing energy supplied from the opposite end of the stretch for causing traffic governing energy to be supplied to the rails of the section at that end of the stretch, means responsive to such traffic governing energy supplied to the rails at said end of the stretch for progressively cutting off the supply of traffic reversing energy to the successive sections in said stretch and for causing the supply of traffic governing energy to be repeated through the successive sections to the end of the stretch and including means responsive to the supply of traffic governing energy over the rails of each section for causing the traffic direction control means to establish the new direction of traffic in such section, and means at each end of the stretch responsive to the traffic governing energy supplied over the rails of the stretch to discontinue the supply of traffic reversing energy thereto.

6. In combination, a stretch of single track railway through which traffic may move in either direction, the rails of said stretch being divided into a plurality of track sections, two sets of coded track circuit apparatus for each section, one for each direction of traffic, each set comprising a code following relay located at the corresponding entrance end of the section responsive to coded energy supplied over the track rails from the other end of the section, traffic direction control means effective at times to cause traffic in each section to be controlled by said coded track circuit apparatus for one direction of traffic and effective at other times to cause traffic in the section to be controlled by said coded track circuit apparatus for the other direction of traffic, means effective when the direction of traffic in the stretch has been established to supply to the corresponding exit end of each section master code energy of a traffic governing code frequency and to supply impulses of feed-back energy to the track rails entrance end of the track stretch, means responsive to feed-back energy supplied to the track rails at the entrance end of the stretch for causing feed-back energy to be supplied successively to the entrance end of the remaining sections of the stretch, a control relay at each end of the stretch for controlling the direction of traffic movements through the stretch and having contacts movable between a first and a second position, each such control relay being effective when its contacts are in their second position to cause traffic governing energy to be supplied to the rails of the stretch at the corresponding end of the stretch and being effective when its contacts are in their first position to permit traffic reversing energy of a distinctive code frequency to be supplied to the rails of the stretch at the corresponding end thereof, means at each end of the stretch effective only when feed-back energy is being received over the track rails at that end of the stretch for moving the contacts of the control relay at that location from their second to their first position, means responsive to traffic reversing energy supplied to the track rails at the end of the stretch for causing energy of this code frequency to be supplied successively to the corresponding ends of the remaining sections of the stretch, means responsive to the supply of said traffic reversing energy over the rails of each section for causing the traffic direction control means to cancel the established direction of traffic in such section, means at each end of the track stretch responsive to the traffic revers-

ing energy supplied from the opposite end of the stretch for moving the contacts of the control relay at that end of the stretch from their first to their second position, means responsive to the traffic governing energy supplied to the stretch at the end opposite to that at which traffic reversing energy is supplied to the stretch for progressively cutting off the supply of traffic reversing energy to the successive sections in said stretch and for causing the supply of traffic governing energy to be repeated through the successive sections to the end of the stretch and including means responsive to the supply of traffic governing energy over the rails of each section for causing the traffic direction control means to establish the new direction of traffic in such section, and means at each end of the stretch responsive to the traffic governing energy supplied over the rails of the stretch to discontinue the supply of traffic reversing energy thereto.

7. In combination, a stretch of single track railway through which traffic may move in either direction, the rails of said stretch being divided into a plurality of track sections, two sets of coded track circuit apparatus for each section, one for each direction of traffic, each set comprising a code following relay located at the corresponding entrance end of the section responsive to coded energy supplied over the track rails from the other end of the section, traffic direction control means comprising a first and a second stick relay at each junction between sections in said stretch, said traffic direction control means being effective when said first stick relays are picked up and said second stick relays are released to cause traffic in each section to be controlled by said coded track circuit apparatus for one direction of traffic and being effective when said first stick relays are released and said second stick relays are picked up to cause traffic in each section to be controlled by said coded track circuit apparatus for the other direction of traffic, means effective when the direction of traffic in the stretch has been established to supply to the corresponding exit end of each section master code energy of a traffic governing code frequency and to supply impulses of feed-back energy to the track rails at the entrance end of the stretch, means responsive to feed-back energy supplied to the track rails at the entrance end of the stretch when the direction of traffic in the stretch has been established to cause feed-back energy to be supplied successively to the entrance ends of the remaining sections of the stretch, means at each end of the stretch for controlling the direction of traffic movements through the stretch comprising means for cutting off the supply of master code energy of traffic governing code frequency to the rails of the section at that end of the stretch and for supplying thereto traffic reversing energy consisting of master code energy of a distinctive code frequency, means responsive to traffic reversing energy supplied to the track rails at the end of the stretch for causing the energized directional stick relays to release successively to thereby cause the master code energy supplied to the corresponding ends of the remaining sections of the stretch to be changed from a traffic governing frequency to the traffic reversing frequency and to cut off the supply of feed-back energy to each of the sections, means at each end of the stretch responsive to the traffic reversing energy supplied from the opposite end of the stretch for causing master code energy of a traffic governing frequency to be supplied to the rails of a traffic governing frequency to be supplied to the rails of the section at that end of the stretch, means re-

the rails of the section at that end of the stretch, means responsive to such traffic governing energy supplied to the rails at said end of the stretch for progressively picking up the directional stick 5 relays which establish the new direction of traffic to thereby cut off the supply of traffic reversing energy to the successive sections in said stretch and to cause the supply of traffic governing energy to be repeated through the successive sections 10 to the end of the stretch, and means at each end of the stretch responsive to the traffic governing energy supplied over the rails of the stretch to discontinue the supply of traffic reversing energy thereto and to cause impulses of feed-back energy 15 to be supplied to the rails of the track stretch at that end thereof.

8. In combination, a stretch of single track railway through which traffic may move in either direction, the rails of said stretch being divided 20 into a plurality of track sections, two sets of coded track circuit apparatus for each section, one for each direction of traffic, each set comprising a code following relay located at the corresponding entrance end of the section responsive to coded energy supplied over the track rails from 25 the other end of the section, traffic direction control means comprising a first and a second stick relay at each junction between sections in said stretch, said traffic direction control means being effective when said first stick relays are picked up and said second stick relays are released to cause traffic in each section to be controlled by said coded track circuit apparatus for one direction of traffic and being effective when 30 said first stick relays are released and said second stick relays are picked up to cause traffic in each section to be controlled by said coded track circuit apparatus for the other direction of traffic, means effective when the direction of traffic 35 in the stretch has been established to supply to the corresponding exit end of each section master code energy of a traffic governing code frequency and to supply impulses of feed-back energy to the track rails at the entrance end of the stretch, means responsive to feed-back energy supplied to the track rails at the entrance end of the stretch when the direction of traffic in the stretch has been established to cause feed-back energy to be supplied successively to the 40 entrance ends of the remaining sections of the stretch, means at each end of the stretch for controlling the direction of traffic movements through the stretch and comprising means effective only when feed-back energy is being received over the track rails at that end of the stretch for cutting off the supply of master code energy of traffic governing code frequency to the rails of the section at that end of the stretch and for supplying thereto traffic reversing energy consisting of master code energy of a distinctive code 45 frequency, means responsive to traffic reversing energy supplied to the track rails at the end of the stretch for causing the energized directional stick relays to release successively to thereby cause the master code energy supplied to the corresponding ends of the remaining sections of the stretch to be changed from a traffic governing frequency to the traffic reversing frequency and to cut off the supply of feed-back energy to each of the sections, means at each end of the 50 stretch responsive to the traffic reversing energy supplied from the opposite end of the stretch for causing master code energy of a traffic governing frequency to be supplied to the rails of the section at that end of the stretch, means re-

sponsive to such traffic governing energy supplied to the rails at said end of the stretch for progressively picking up the directional stick relays which establish the new direction of traffic to thereby cut off the supply of traffic reversing energy to the successive sections in said stretch and to cause the supply of traffic governing energy to be repeated through the successive sections to the end of the stretch, and means at each end of the stretch responsive to the traffic governing energy supplied over the rails of the stretch to discontinue the supply of traffic reversing energy thereto and to cause impulses of feed-back energy to be supplied to the rails of the track stretch at that end thereof.

9. In combination with a stretch of track over which traffic may move in either direction, said stretch being divided into a plurality of track sections, means effective when traffic in said stretch has been established in either direction to supply master code energy of a traffic governing code frequency to the corresponding exit end of each track section, traffic reversing means at each end of the stretch for changing that end of the stretch from an exit to an entrance end and comprising means to discontinue the supply of master code energy of a traffic governing frequency to the rails of the stretch and for supplying thereto traffic reversing energy comprising master code energy of a distinctive code frequency, means for each section effective on the supply of traffic reversing energy thereto at either end to supply energy of this code frequency to the rails of the adjacent section to thereby cause energy of this code frequency to be cascaded to the existing entrance end of the stretch, means at each end of the stretch operative on the supply thereto of traffic reversing energy over the rails of the track stretch to supply master code energy of a traffic governing code frequency to the track rails at that end of the stretch, means for each section operative on the supply thereto of traffic governing energy at the new exit end thereof to cut off the supply of traffic reversing energy to the section rails and to cause traffic governing energy to be supplied to the rails of the adjacent section to thereby cause the supply of traffic reversing energy to be progressively cut off and to cause the supply of traffic governing energy to be cascaded to the new entrance end of the stretch, and means at each end of the stretch responsive to the supply of traffic governing energy over the rails of the stretch for controlling entrance of traffic into the stretch.

10. In combination with a stretch of track over which traffic may move in either direction, said stretch being divided into a plurality of track sections, means effective when traffic in said stretch has been established in either direction to supply master code energy of a traffic governing code frequency to the corresponding exit end of each section and to supply impulses of feed-back energy to the corresponding entrance end of the stretch and to cause the supply of feed-back energy to be repeated through successive track sections to the corresponding exit end of the stretch provided the stretch is vacant, traffic reversing means at each end of the stretch for changing that end of the stretch from an exit to an entrance end and comprising means effective only when feed-back energy is being received at the end of the stretch to discontinue the supply of master code energy of a traffic governing frequency to the rails of the stretch and for supply-

ing thereto traffic reversing energy comprising master code energy of a distinctive code frequency, means for each section effective on the supply of traffic reversing energy thereto at either end to supply energy of this code frequency to the rails of the adjacent section to thereby cause energy of this code frequency to be cascaded to the existing entrance end of the stretch, means at each end of the stretch operative on the supply thereto of traffic reversing energy over the rails of the stretch to supply master code energy of a traffic governing code frequency to the track rails at that end of the stretch, means for each section operative on the supply thereto of traffic governing energy at the new exit end thereof to cut off the supply of traffic reversing energy to the section rails and to cause traffic governing energy to be supplied to the rails of the adjacent section to thereby cause the supply of traffic reversing energy to be progressively cut off and to cause the supply of traffic governing energy to be cascaded to the new entrance end of the stretch, and means at each end of the stretch responsive to the supply of traffic governing energy over the rails of the stretch for controlling entrance of traffic into the stretch.

11. In combination with a stretch of track over which traffic may move in either direction, said stretch being divided into a plurality of track sections, two sets of coded track circuit apparatus for each section, one for each direction of traffic, each set comprising a coding relay located at the corresponding exit end of the section for supplying coded energy to the section rails and a code following track relay located at the corresponding entrance end of the section responsive to coded energy supplied over the section rails, means for each section effective when the direction of traffic in the stretch has been established to supply to the coding relay at the corresponding exit end of the section coded energy of a traffic governing code frequency, traffic reversing means at each end of the stretch for changing that end of the stretch from an exit to an entrance end and comprising means to discontinue the supply of master code energy of a traffic governing frequency to the coding relay at that end of the stretch and for supplying thereto traffic reversing energy comprising master code energy of a distinctive code frequency, means for each track relay except the track relays at the ends of the stretch effective on operation of the track relay by energy of traffic reversing frequency to discontinue the supply of coded energy of traffic governing frequency to the coding relay at the adjacent end of the adjacent track section and to establish for such coding relay a circuit including a contact of the track relay to thereby cause energy of traffic reversing frequency to be cascaded throughout the stretch, means at each end of the stretch operative on the supply thereto of traffic reversing energy over the rails of the stretch to supply coded energy of traffic governing frequency to the coding relay at the adjacent end of the track section at that end of the track stretch, each track relay except the track relays at the ends of the stretch having associated therewith means effective on operation of the relay by energy of traffic governing frequency to interrupt the circuit for supplying coded energy of traffic reversing frequency to the coding relay at that end of the track section and to cause coded energy of traffic governing frequency to be supplied to the coding relay at the adjacent end of the adjacent section, and means at each end of

the track stretch responsive to operation of the track relay at that end of the stretch by coded energy of a traffic governing frequency to cut off the supply of coded energy of traffic reversing frequency to the coding relay at that end of the stretch and to control a signal governing entrance of traffic into the stretch.

12. In combination with a stretch of track over which traffic may move in either direction, said track stretch being divided into a plurality of track sections, two sets of coded track circuit apparatus for each section, each set comprising a coding relay located at the corresponding exit end of the section for supplying coded energy to the section rails and a code following track relay located at the corresponding entrance end of the section responsive to coded energy supplied over the section rails, means effective when the direction of traffic in the stretch has been established to supply to the coding relay at the corresponding exit end of each section coded energy of a traffic governing code frequency, means effective when the direction of traffic in the track stretch has been established to cause the coding relay at the corresponding entrance end of the stretch to operate to supply impulses of feed-back energy to the rails of the associated track section and to cause the coding relay at the corresponding entrance end of each of the other track sections in the track stretch to operate to supply impulses of feed-back energy to the corresponding entrance end of the associated track section provided feed-back energy is being received at the adjacent end of the adjacent section, traffic reversing means at each end of the stretch for changing that end of the stretch from an exit to an entrance end and comprising means operative only when feed-back energy is being received at that end of the stretch to change the coded energy supplied to the coding relay at that end of the stretch from a traffic governing code frequency to traffic reversing energy of a distinctive code frequency, means for each track relay except the track relays at the ends of the stretch effective on operation of the track relay by energy of traffic reversing frequency to discontinue the supply of coded energy of traffic governing frequency to the coding relay at the adjacent end of the adjacent track section and to establish for such coding relay a circuit including a contact of the track relay to thereby cause energy of traffic reversing frequency to be cascaded throughout the stretch, means at each end of the stretch effective on operation of the track relay at that end of the stretch by coded energy of traffic reversing code frequency to supply coded energy of traffic governing code frequency to the coding relay at the adjacent end of the track section at that end of the track stretch, each track relay except the track relays at the ends of the stretch having associated therewith means effective on operation of the relay by energy of traffic governing frequency to interrupt the cir-

5 circuit for supplying coded energy of traffic reversing frequency to the coding relay at that end of the track section and to cause coded energy of traffic governing frequency to be supplied to the coding relay at the adjacent end of the adjacent section, and means at each end of the track stretch responsive to operation of the track relay at that end of the stretch by coded energy of a traffic governing frequency to control a signal governing entrance of traffic into the stretch and to cut off the supply of coded energy of traffic reversing frequency to the coding relay at that end of the stretch and condition said coding relay to supply impulses of feed-back energy to the rails of the associated section.

10 13. In coded track circuit signaling apparatus for adjacent ends of adjacent first and second sections in a single track stretch over which traffic may move in either direction, a code following track relay for each section operated by energy supplied over the rails of the associated section, a coding relay for each section governing the supply of coded energy to the section rails, a first and a second directional stick relay, means effective when the first directional stick relay is energized to supply coded energy of a traffic governing code frequency to the coding relay for the second section, means effective when the second directional stick relay is energized to supply coded energy of a traffic governing code frequency to the coding relay for the first section, means responsive to operation of the track relay for the first section by traffic reversing energy of a distinctive code frequency to cut off the supply of coded energy of traffic governing code frequency to the coding relay for the second section, to release the first directional stick relay and to thereafter establish a circuit including a back contact of the second directional stick relay and a contact of said track relay for supplying energy to the coding relay for said second section, means responsive to operation of the track relay for the second section by traffic reversing energy of said distinctive code frequency to cut off the supply of coded energy of traffic governing code frequency to the coding relay for the first section, to release the second directional stick relay and to thereafter establish a circuit including a back contact of the first directional stick relay and a contact of said track relay for supplying energy to the coding relay for said first section, means responsive to coding operation of the track relay for the second section when the track relay for the first section is operated by traffic reversing energy to establish a pick-up circuit for said second directional stick relay, and means responsive to coding operation of the track relay for the first section when the track relay for the second section is operated by traffic reversing energy to establish a pick-up circuit for said first directional stick relay.

ARTHUR L. JEROME.
